UNITED STATES PATENT OFFICE.

GEORGE E. HART, OF NEWARK, NEW JERSEY, ASSIGNOR TO THE HORNUM PATENT REGISTER MANUFACTURING COMPANY.

IMPROVEMENT IN FARE-REGISTERS.

Specification forming part of Letters Patent No. **218,735**, dated August 19, 1879; application filed June 5, 1879.

To all whom it may concern:

Be it known that I, GEORGE E. HART, of Newark, in the county of Essex and State of New Jersey, have invented a new and useful Improvement in Fare-Registers, which improvement is fully set forth in the following specification, reference being had to the accompanying drawings, in which—

Figure 1 is a plan or top view of my register. Fig. 2 is a vertical longitudinal section thereof. Fig. 3 is a vertical cross-section of the same in the plane of the line $x-x$, Fig. 2. Fig. 4 is a like section thereof in the plane of the line $y-y$, Fig. 2. Figs. 5, 6, 7, and 8 are detail views of parts. Fig. 9 is a perspective view of one end of the casing, &c.

Similar letters indicate corresponding parts.

My invention relates especially to that class of registers intended to be put up in railway-cars and other public conveyances so as to form permanent fixtures therein; and it consists in certain novel combinations of parts, hereinafter fully described, and pointed out in the claims, a preliminary description thereof being therefore deemed unnecessary.

In the drawings, the letter A designates the inclosing-case of my register, having suitable openings to expose the registering devices, and B is a cylinder fastened to heads or standards C C' at the ends of the inclosing-case. On this cylinder B are fitted two sets of rings, D¹ D² D³ and E¹ E² E³ E⁴, the first forming a reversible register and the last-named a permanent register. On the cylinder is also fitted a ring, G, forming a trip-indicator.

The several rings D¹, &c., E¹, &c., and G are loose on the cylinder B, and each ring is held stationary in the different positions to which it may be moved by means of a spring or detent, *a*, secured upon the cylinder, as shown in Fig. 4.

The heads C C' of the cylinder form bearings for a rock-shaft, F, which has a handle, *b*, combined with a spiral spring, *b'*, for imparting thereto the required motions, and which carries pawls *c* *c'* *d¹* *d²* *d³*. The shaft F also carries a sleeve, H, to which is attached a pawl, *e*. The several pawls *c*, *c'*, *d¹*, *d²*, *d³*, and *e* project through the side of the cylinder B, which, to this end, is provided with suitable slots, and

they catch, respectively, in one of a series of notches, *h*, formed on the inner faces of the rings.

The pawls *c* and *c'* are attached to the rock-shaft F by means of arms *q* *r*, and they engage, respectively, the unit-rings D¹ and E¹ of the reversible and permanent registers, their functions being to advance such rings.

The pawls *d¹* *d²* *d³* are attached to the rock-shaft F by means of arms *s* *t*, and they engage the three rings D¹ D² D³ of the reversible register, serving to retract or turn back these rings.

The sleeve H is loose on the shaft F, and its pawl *e* serves to set the trip-indicator G.

Each of the rings D¹ D² D³ of the reversible register contains a longitudinal slot, *g*, adapted to receive one of the retracting-pawls *d¹* *d²* *d³*, and these pawls are arranged to engage such rings in the lines of the slots, as indicated in Fig. 7.

From the rock-shaft F projects an arm, *i*, carrying a cam, *j*, which is movable upon the arm in a radial direction, and which is fitted in a transverse slot or opening, *o*, at the end of the cylinder B, as seen in Fig. 4, a spring, *u*, being placed within or beneath it to force the same outward. The slot *o* is provided with an inner bevel, *p*, at one end.

In the path of the cam *j* is situated a pin, *k*, which passes transversely through the unit-ring D¹ of the reversible register, and projects therefrom under normal conditions, the same being forced outward by the action of a spring, *l*.

In the second or ten-ring, D², of the reversible register is arranged a spring-impelled pin, *m*, whose length is equal to the width of said ring, and in both the ten-ring D² and the hundred-ring D³ is a series of holes, *n*, the number of which is equal to the faces or figures on the rings, and which are in the line or path of the pins *k* *m*.

The cam *j* acts on the pin *k* in the forward motion of the unit-ring D¹, and drives this pin into one of the holes *n* of the ten-ring D², while this pin has a like action on the pin *m*, driving the same into one of the holes of the hundred-ring D³, as indicated in Fig. 6, and as hereinafter more fully explained.

A cam, *v*, is fastened to the arm *t* upon the

rock-shaft F, as shown in Fig. 2, for the purpose of actuating pins arranged in the rings E¹, &c., of the permanent register in a similar manner to the action of the cam j upon the pins of the reversible register.

The arrangement of the pins of the permanent register being identical with that of the pins of the reversible register, a detail view of the same is deemed unnecessary.

From the sleeve H, which carries the pawl e for actuating the trip-register G, projects a handle, I, the shank of which is fitted in a slot formed in the side of the cylinder B, and which serves, among other things, to impart the required motion to the sleeve and pawl.

Two spurs, w w', (see Figs. 2 and 4,) are attached to the handle I, one above the other, at a point within the cylinder B, and a lever, J, is hung lengthwise within the cylinder in such a manner that its one end is within the extremities of and adjacent to the spurs, at which end the lever is provided with a double bevel, as shown in Fig. 5.

Near its opposite end the lever J carries pins y¹ y² y³, which project upward through the cylinder B, and are adapted to catch in notches or holes y⁴, formed on the inner faces of the reversible rings D¹ D² D³.

The spurs w w' are beveled in opposite directions, and are connected to springs, whereby they are adapted to yield.

The lever J has its fulcrum on a pin, z, and its beveled end is pressed downward by the action of a spring, x¹, while it is steadied sideways by bars x².

In addition to the spurs w w', the handle I carries a pin, 10, which projects in an opposite direction to the spurs, and which works in a slot, 11, formed in the adjacent cylinder-head C, this slot being curved, and being concentric with the shaft F.

The pin 10 acts upon a double stop-pawl, K, (best seen in Fig. 3,) which, in conjunction with a cam-disk, L, firmly secured upon the rock-shaft F, serves to regulate the motions of this shaft, the cam-disk being provided with two shoulders, 12 13, on its edge, with one of which the stop-pawl engages, according to its position.

The cam-disk L is also provided with teeth 14 adjacent to the shoulder 12, and with a notch, 15, which latter is adapted to receive a spur projecting from a spring, N, which bears on the stop-pawl K.

A spring-catch, O, is combined with the stop-pawl K to engage a spur, 16, projecting therefrom.

On the face of the cam-disk L is arranged a trip-pawl, P, in the path of which is situated a bell-crank, Q, acted upon by a spring, 17, and carrying a hammer, R, which is combined with a bell, S, to form an alarm.

The trip-pawl P is held in its working position by a spring, 18, and with the same is combined a spring-catch, 22, which is attached to the cam-disk, so as to move therewith, and in the path of which is arranged a releasing-toe,

21. The bell S is inclosed in a case, T, which is perforated.

The operation of my machine is as follows: When a fare is to be registered the rock-shaft F is turned in the direction of the arrow indicated in Fig. 4 by moving the handle b through the line of the arrow 19, Fig. 3, the shaft being returned to its normal position by the action of the spring b' upon the handle. By this motion of the shaft E (which may be termed its "forward motion") the pawls c c' are pushed forward and caused to act on the unit-rings D¹ and E¹ of the reversible and permanent registers, so as to move both of these rings forward one step, the retracting-pawls d¹ d² d³ being at the same time drawn back, owing to their connection with the shaft.

During each revolution of the unit-rings D¹ or E¹, the pins projecting therefrom (as the pin k of the ring D¹) are pushed inward by the action of the cams j and v, and, entering one of the holes of the next or ten rings, D² E², move these rings forward one step, the pin k returning to its outer position when this step has been made. Once in every revolution of the ten-rings D² E² their pins (as the pin m of the wheel D²) come opposite the pins of the unit-wheels D¹ E¹, and, as the latter pins are driven inward by means of the cams j v, they act upon said pins of the ten-rings, and cause these pins to engage the hundred-rings D³ E³, as indicated in Fig. 6, so as to move the latter rings forward one step. This action is repeated in proper order on the fourth wheel, E⁴, of the permanent register. A registry is thus made by the reversible register and the permanent register simultaneously; but when the first-named register is set back the permanent register remains unchanged.

When it is desired to reverse the rings D¹ D² D³ of the reversible register, the shaft F is turned in an opposite direction to the arrow shown in Fig. 4, this motion (which may be termed the "back motion" of the shaft) being produced by moving the handle b through the line of the arrow 20, Fig. 3. By this back motion of the shaft F the pawls d¹ d² d³ are pushed forward, and, acting on the rings D¹ D² D³, produce a reverse motion of these rings.

The action of the pawls d¹ d² d³ on the rings D¹ D² D³ continues until the pawls drop into the slots g of the rings, when they simply play in these slots and have no further action. The slots g are so arranged relatively to the figures on the rings D¹ D² D³ that when the pawls d¹ d² d³ fall into the same the rings shall be at zero.

In the back motion of the shaft F the cam moves in the direction of the apron I, (shown in Fig. 4,) and the inclined edge j' of said cam comes in contact with the bevel p at the end of the slot o, whereby the cam is pushed inward against the action of the spring u a sufficient distance to allow the pin k to clear the same. When it is desired to give the shaft F a forward motion, the stop-pawl K is tipped to engage the shoulder 12 of the cam-disk L

as shown in Fig. 3, by moving the handle I, carrying the pin 10, to the position shown.

If the shaft F is then turned forward, the shoulder 12 of the cam-disk moves away from the pawl K, but is caught on its return, and by this means what I have termed the "back-motion" of the shaft is prevented. On the other hand, if the pawl K is tipped to engage the shoulder 13 of the cam-disk, a back motion may be given to the shaft F, since this shoulder 13 moves away from the pawl during this motion; but a forward motion of the shaft is prevented, owing to the contact between the shoulder 13 and the pawl K on the return of the shaft from its back motion.

When the handle I is moved to the position shown—namely, to hold the pawl K in a position to allow the forward motion of the shaft F—the sleeve H is turned on the shaft F a sufficient distance to cause its pawl e to advance the trip-indicator G one step. In other words, a registry must be made by the trip-indicator each time the reversible register has been set back and is again to be advanced.

When the rings D¹ D² D³ of the reversible register reach the zero-point, the pins y¹ y² y³ of the lever J, Fig. 2, enter the notches or holes y⁴ of said rings, and this lever assumes the position shown. The handle I can then be moved to the position shown—namely, to allow the forward motion of the shaft F and to set the trip-register G, its lower spur, w', coming in contact with the lower level at the end of the lever J, and, the spur being adapted to yield, permitting the handle to pass the lever; but the handle at the same time is prevented from being returned to its other position except the lever J is displaced to allow the spur w' to clear the same. This displacement of the lever J occurs when the unit-ring D¹ of the reversible register is advanced—that is to say, this unit-ring, upon turning, drives the pin y¹ out of its notch y⁴, thereby moving such pin and the end of the lever inward. Hence the handle I cannot be moved back or out of the position shown until the reversible register D¹, &c., has been advanced to register one or more fares, and the trip-indicator can be set only once each time the reversible register is set back.

When the handle I is moved back or out of the position shown, its lower spur, w', clears or passes under the lever J, while the upper spur, w, strikes the upper bevel at the end of the lever and rides over the same, so as to take its place, together with the lower spur, w', on the opposite side of the lever. This upper spur, w, then stands in the way of another movement of the handle I to the position shown until the reversible register D¹, &c., is set back to zero, and the lever J resumes the position indicated.

The lever J thus permits the setting of the trip-register G only when the reversible register is at zero, besides preventing its being set more than once, as before stated.

At each forward motion of the shaft F the trip-pawl P upon the cam-disk L comes in contact with the bell-crank Q, and, displacing this crank, causes the hammer R to strike the bell S. It follows that the alarm is sounded as often as a registry is made.

As the trip-pawl P displaces the bell-crank Q it passes over or beyond the latter, and on its return said pawl is lifted by contact with the crank, and is caught by the spring-catch 22, whereby it is held in an upper position. In this position the pawl P clears the bell-crank Q, and hence it can have no further action on the crank until released from the catch. This occurs on the return of the rock-shaft F from its forward motion—that is to say, on such return the spring-catch 22 strikes the releasing-toe 21, as shown in Fig. 3, and is thereby raised, so as to release the pawl. The result of this arrangement is, that the trip-pawl P cannot be made to act on the bell-crank Q without the necessary motion of the shaft F to make a registry.

In the forward motion of the cam-disk L, together with the shaft, the spur projecting from the spring N is driven out of the notch 15 of the disk, and this spring is forced back, so as to cease its action on the stop-pawl K. This pawl then engages the teeth 14, and prevents the return of the cam-disk L until the pawl has passed the last tooth and reaches a higher point, when it is caught by the spring-catch O and held in an upper position, so as to clear the teeth and allow the return of the disk.

The pawl K is held by the spring-catch O until the spring N is permitted to resume its first position by the falling of its spur into the notch 15, which takes place on the return of the cam-disk L from its forward motion, in which position the spring N bears on the pawl and disengages the same from the catch.

What I claim as new, and desire to secure by Letters Patent, is—

1. The combination, in a fare-register, of a stationary cylinder, two sets of rings fitted upon said cylinder, one forming a reversible register and the other a permanent register, a rock-shaft extending through the cylinder, two advancing-pawls attached to the shaft, one acting upon the reversible register and the other upon the permanent register, a series of pawls attached to said shaft for retracting the reversible register, mechanism for regulating the motions of the shaft, and alarm mechanism, all constructed and adapted to operate substantially as described.

2. The combination, in a fare-register, of a stationary cylinder, a set of rings fitted upon said cylinder to form a reversible register, each provided with a longitudinal slot, a rock-shaft extending through the cylinder, a pawl attached to said shaft for advancing the reversible register, a series of pawls attached thereto for retracting such register, arranged to enter the slots of the rings at zero, mech-

anism for regulating the motions of the shaft, and alarm mechanism, all constructed and adapted to operate substantially as described.

3. The combination, in a fare-register, of a stationary cylinder, a set of rings fitted upon said cylinder, forming a reversible register, a ring fitted upon said cylinder to form a trip-indicator, a rock-shaft extending through the cylinder, an advancing-pawl and a series of retracting-pawls acting upon the reversible register attached to the shaft, a sleeve fitted on said shaft, carrying a pawl to set the trip-indicator, a handle projecting from said sleeve, a lever arranged in the described relation to the reversible register and said handle to control the trip-indicator, mechanism for regulating the motions of the shaft, and alarm mechanism, all constructed and adapted to operate substantially as described.

4. The combination, in a fare-register, of a stationary cylinder, a series of rings fitted upon said cylinder, forming a reversible register, a ring fitted upon the cylinder to form a trip-indicator, a rock-shaft extending through the cylinder, an advancing-pawl and a series

of retracting-pawls acting upon the reversible register attached to the shaft, a sleeve fitted on said shaft, carrying a pawl to set the trip-indicator, a handle projecting from said sleeve, a lever arranged in the described relation to the reversible register and said handle to control the trip-indicator, mechanism for regulating the motions of the shaft, and alarm mechanism, all constructed and adapted to operate substantially as described.

5. The combination, with the cam-disk L and double stop-pawl K, of the spring-catch O and spring N, substantially as and for the purpose described.

6. The combination, with the cam-disk L, of the trip-pawl P, for acting on the bell-hammer, the spring-catch 22, and releasing-toe 21, substantially as and for the purpose described.

In testimony that I claim the foregoing I have hereunto set my hand and seal this 4th day of June, 1879.
